114,201

DESIGN FOR A COMBINATION REAMER, JUICE STRAINER, AND EXTRACTOR

Rudolph Richard Spira, New York, N. Y.

Application July 12, 1938, Serial No. 78,423

Term of patent 3½ years

To all whom it may concern:

Be it known that I, Rudolph Richard Spira, a citizen of the United States of America and resident of the city of New York, county of New York, and State of New York, have invented a new, original, and ornamental Design for a Combination Reamer, Juice Strainer, and Extractor, of which the following is a specification, reference being had to the accompanying drawing, forming part thereof.

In the drawing:

Fig. 1 is a top plan view of the combination

reamer, juice strainer, and extractor, showing my design;

Fig. 2 is a side elevational view thereof, on a reduced scale;

Fig. 3 is a cross-sectional view taken along line 3—3 of Fig. 2; and

Fig. 4 is a cross-sectional view taken along line 4—4 of Fig. 2.

I claim:

The ornamental design for a combination reamer, juice strainer, and extractor, as shown.

RUDOLPH RICHARD SPIRA.
